Attn:

UNITED STATES PATENT OFFICE.

ARNOLD W. ZIMMERMAN, OF WASHINGTON HEIGHTS, ILLINOIS, ASSIGNOR
OF ONE-HALF TO F. W. BIRD & SON, OF WALPOLE, MASSACHUSETTS.

CAR-ROOFING.

SPECIFICATION forming part of Letters Patent No. 446,244, dated February 10, 1891.

Application filed June 13, 1890. Serial No. 355,344. (No model.)

To all whom it may concern:

Be it known that I, ARNOLD W. ZIMMERMAN, a citizen of the United States, residing at Washington Heights, in the county of 5 Cook and State of Illinois, have invented certain new and useful Improvements in Car-Roofing, of which the following is a specification.

My invention relates to a car-roofing where-
10 in a lining of paper, cloth, or other flexible
material is secured over the roof-boards of
cars, and the invention is particularly applica-
ble to the construction of what are termed
"refrigerator-cars;" and the object of my in-
15 vention is to so secure the paper or cloth lin-
ing to the sheathing of the car as to prevent
the leakage therethrough of water which finds
its way through the covering, following the
nails or other fastenings. This object I ac-
20 complish by securing to the sheathing strips
over which the paper, or similar lining is
spread, and the nails or other fastening de-
vices are driven through the paper and through
or into these strips. By this means the up-
25 per end of the perforation is above the plane
of the body of the material, and consequently
water which finds its way through the outer
covering of the car is prevented from enter-
ing these apertures and following the nails
30 through the lining. Over these strips are se-
cured cap-pieces which are grooved out on
their lower sides, so as to clamp the paper se-
curely upon the strips and to cover the fast-
enings, thereby making a better joint. Upon
35 these cap-pieces are secured the purlins which
support the outer roof-boards.

In the accompanying drawings, Figure 1 is
a perspective view of a portion of the car-roof,
partly in section; and Fig. 2 is a sectional de-
40 tail through the sheathing lining and strip,
showing also a cap-piece fitting over the strip
and a fastening-screw, the latter being shown
in dotted lines.

In the drawings, A represents the carlings,
45 and B the sheathing of the roof. Upon this
sheathing at suitable intervals, are placed
strips C, extending from the edge to the comb
of the roof, and which strips are preferably
of the form known as "half-round," as when

paper is used for a lining it can be the more 50
readily conformed to a strip having a rounded
surface without breaking.

The lining D, which may be of paper, cloth,
or other suitable flexible material, is then
spread over the sheathing and strips and fitted 55
closely to the latter, and then a cap E, having
a longitudinal groove in its lower side of the
configuration of the strip, is applied over the
strip and paper or other lining and fastened
by means of nails or screws, as indicated by 60
the dotted lines e, Fig. 2, the fastening per-
forating the lining on its passage into the
strip. It will be observed that the paper or
other lining at the point where it is perforated
by the passage of the securing nails or screws 65
is elevated above the plane of the body of the
paper lying upon the sheathing, and there-
fore water which may find its way through the
outer covering is prevented from passing
through the lining, the latter being imperfo- 70
rate in its level portion.

The purlins F may be placed across the
cap-pieces, and upon these are secured the
outer roof-boards G. The lining can be ob-
tained in sheets of sufficient size to cover one- 75
half of the car-top—i. e., from the edge of the
roof to the comb—the sheet being placed with
its greatest length longitudinally of the car;
but if a plurality of pieces be used I prefer
to form the joints beneath the cap, as the wa- 80
ter is thereby the better excluded.

A car constructed as above described will
be practically air and water tight, and the
circulating-air space between the outer cov-
ering and the lining will assist to prevent the 85
radiation of heat.

I claim—

1. The herein-described improvement in
car-roofing, comprising, in combination with
the sheathing-strips secured thereon and ex- 90
tending from the edge of the roof to the comb
or ridge, a lining of paper or like flexible
material secured over said strips by fasten-
ings passed through the lining at its elevated
portion and into the strips, and cap-pieces ex- 95
tending also from the edges of the roof to the
comb, having grooves in their lower faces
and adapted to fit closely upon the strips and

cover the fastenings, and purlins secured upon the cap-pieces to support the outer roof-covering, substantially as described.

2. The herein-described improvement in 5 car-roofing, comprising, in combination with the sheathing, rounded strips secured thereon and extending from the edge of the roof to the comb or ridge, a lining of paper or like flexible material secured over said strips by 10 fastenings passed through the lining at its elevated portion and into the strips, and cap-pieces extending also from the edges of the roof to the comb, having grooves in their lower faces and adapted to fit closely upon 15 the rounded strips and cover the fastenings, and purlins secured upon the cap-pieces to support the outer roof-covering, substantially as described.

3. The herein-described improvement in 20 car-roofing, comprising, in combination with

the sheathing, rounded strips secured thereon and extending from the edge of the roof to the comb or ridge, a lining of paper or like flexible material, said lining consisting of continuous sheets, each adapted to cover one 25 side of the car-roof from the edge thereof to the comb or ridge and secured over said strips by fastenings passed through the lining at its elevated portion and into the strips, and cap-pieces extending also from the edges of the 30 roof to the comb, having grooves in their lower faces and adapted to fit closely upon the rounded strips and cover the fastenings, and purlins secured upon the cap-pieces to support the outer roof-covering, substantially 35 as described.

ARNOLD W. ZIMMERMAN.
